US0D1085815S

(12) **United States Design Patent** (10) **Patent No.:** **US D1,085,815 S**
(45) **Date of Patent:** **** Jul. 29, 2025**

(54) **BLENDER CONTAINER**

(71) Applicant: **SharkNinja Operating LLC**,
Needham, MA (US)
(72) Inventor: **Joyce Chien Tu**, Melrose, MA (US)
(73) Assignee: **SharkNinja Operating LLC**,
Needham, MA (US)
(**) Term: **15 Years**
(21) Appl. No.: **29/909,685**
(22) Filed: **Aug. 9, 2023**

(57) **CLAIM**

The ornamental design for a blender container, as shown and described.

DESCRIPTION

FIG. 1 is a perspective view of a blender container showing my new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines in the drawings depict portions of the blender container form no part of the claimed design.

1 Claim, 7 Drawing Sheets
